UNITED STATES PATENT OFFICE.

THOMAS C. ROBINSON, DECEASED, LATE OF EVERETT, MASSACHUSETTS, BY ELIZABETH J. SAVAGE, ADMINISTRATRIX.

INVALID-BEDSTEAD.

1,021,335.

Specification of Letters Patent. Patented Mar. 26, 1912.

Application filed May 11, 1911. Serial No. 626,607.

To all whom it may concern:

Be it known that THOMAS C. ROBINSON, late a citizen of the United States and resident of Everett, in the county of Middlesex and State of Massachusetts, deceased, did invent certain new and useful Improvements in Invalid-Bedsteads, of which the following is a specification.

This invention relates to adjustable bedsteads especially designed for use of invalids, the mattress supporting frame, constituting a bed frame, but so supported by the main frame that the bed frame may be transversely tipped or laterally inclined, and positively secured at any position within the limits of its adjustability so that one longitudinal edge may be raised while the other is simultaneously depressed.

The invention has for its object to provide a bedstead of this character which will enable a patient to have his position changed without being obliged to touch his body or prop him in different positions by means of pillows or other articles.

Another object of the invention is to provide a bedstead which can be secured in any one of a wide range of laterally or longitudinally inclined positions.

The invention consists in the improvements which I will now proceed to describe and claim.

Of the accompanying drawings, forming a part of this specification,—Figure 1 is a side elevation of a bedstead embodying my invention, the screw shaft which enables the lateral adjustment to be effected being omitted. Fig. 2 is an end view from the right of Fig. 1. Fig. 3 represents a detail, partly in section and on a larger scale, of some of the operating mechanism and gearing. Fig. 4 is a detail sectional view of one of the springs for supporting the intermediate portion of the spring mattress.

Similar reference characters indicate the same or similar parts in all of the figures.

The main frame comprises a suitable head 10 and foot 11 connected by side rails 12, and having a cross bar 13 at each end which is elevated (see Fig. 2) considerably above the plane of the side rails 12 to provide the longitudinal pivotal support 18, hereinafter described, at the proper elevation so that when the mattress frame is tilted the lower edge will not pass below a side rail 12.

The bed or mattress frame comprises a

head section 14 and a foot or body section 15 which are pivotally connected at 16 and carry any suitable or preferred wire mattress 17. The sections 14, 15 as a whole comprise the support for the wire mattress 17. 60 Pivoted at 18 to each of the end bars 13 is a frame 19, of an inverted U-shape, the two frames 19 being connected by longitudinal rods 20, so that the two frames 19 and the rods 20 may swing together on the pivots 65 18. One frame 19 has a fixed pendent arm 21 to the lower end of which is pivoted a nut 22. A screw shaft 23 passes through said nut and has a crank 24 at its outer end, said crank being preferably a removable 70 one. A suitable supporting bracket for the outer end of said screw shaft 23 is shown at 25 in Fig. 2.

The rods 20 are connected by transverse bars 26, one beneath the section 14 and the other beneath the section 15. As the mechanisms for longitudinally tilting the sections 14, 15 are the same a description of one will suffice for both. The bar 26 has bearings 27, 28 for a shaft 29, the outer end of which has a crank or is formed to be engaged by a removable crank. The inner end of the shaft carries a pinion 30. Suitably mounted as by means of the shaft 29 is a bracket 31 having a vertical bearing 32. A nut 33 is 85 mounted in said bearing and is formed with an annular groove 34 which is engaged by a screw 35 to retain said nut against longitudinal movement in its bearing while permitting it to rotate therein. The nut carries a pinion 36 which meshes with the pinion 30, and a screw 37 passes through said nut. Said screw is pivotally connected at its upper end to a rod 38 supported by ears 39 carried by the adjustable section. It will 90 now be understood that, by operating the screw shaft 23, the entire bed frame including the two sections 14 and 15 may be swung upon the pivots 18 and secured in practically any laterally inclined position desired. 100 By actuating the shafts 29, the sections 14, 15 may be inclined longitudinally of the bedstead as indicated by the dotted lines in Fig. 1. By adjusting one section upwardly and the other downwardly on pivot or center 16, the mattress may be fixed in one plane but inclined so that either the head end or the foot end may be the highest. Or either section can be adjusted so as to change its angle relatively to the other to any de- 110

gree that is liable to be desired. All of the 5 adjustments can be effected without disturbing the patient, his body simply following the varying inclinations with perfect ease.

10 The support for the pivotal joints 16 is provided by straps 40 the lower ends of which are mounted on the rods 20, and the upper portions of said straps are connected by a transverse bar 41, the plane of said 15 bar 41 being considerably below that of the wire mattress 17. Said bar 41 carries yielding supports for the pivotal portion of the wire mattress at the point where the greatest weight is usually applied. Said bar 41 has secured thereto a row of sockets 42, a 20 plunger 43 being mounted in each of said sockets and having a stem 44 which is surrounded by a coil spring 45 inclosed within the socket. The upper ends of the plungers 25 43 are connected to the wire mattress 17 and therefore, when the sections 14, 15 are adjusted upwardly, the plungers 43, owing to their attachment to the wire mattress 17, will hold that transverse portion of the 30 mattress from riding. The plungers 43 are limited as to their upward movement by pins 46 extending through the stems 44 below the bottom of the sockets. To sustain the middle portion of the bar 41, a suitable truss such as indicated at 47 in Fig. 2, may 35 be connected to the rods 20 and to said bar 41.

As shown by comparing Figs. 1 and 2, each section 14, 15, is of a length so that its 40 end may pass up or down inside the upper cross bar of frame member 19, and each section 14, 15, is supported by the vertically adjustable cross rod 38 and by the pivots 16. Since the pivots 16 are supported by 45 the straps 40, and the latter by the rods 20, which are connected to the laterally swinging frames 19 pivotally supported at 18 to the fixed end bars 13, it is obvious that when the frame comprising the 50 members 19, 20, is swung on pivots 18 by rotating the shaft 23, the members 26, the gearing shown in Fig. 3, the rods 38, the straps 40, bar 41, pivots 16, and sections 14, 15, all swing as one, while still permitting the sections 14, 15, to be independently 55 adjusted as indicated by the dotted lines in Fig. 1, no matter what may be the lateral inclination secured by the shaft 23.

One especial reason for holding the bed 60 frame or mattress securely in a laterally inclined position is to enable irrigation of the patient to be performed without turning the patient on his side. The structure illustrated enables the patient's body to be inclined laterally to the right or left while still actually lying on his back. Another reason for the adjustment to any fixed lateral inclination is to be able to meet a patient's wishes for changes of position, without having to touch his body or prop him

in the desired position with pillows or other articles. And this applies also to the means for adjusting, and holding the adjustment of, the sections in a longitudinal direction. In other words, a patient who becomes 70 restless and desirous of changes of position, can have his position changed to a fraction of an inch in any direction, without lifting any part of his body, or doing any proping, and it is done easily and noiselessly, 75 and without chance of the adjusted position being unintentionally disturbed.

What is claimed is:

1. An adjustable bedstead comprising a main frame, a bed frame, connections between said parts permitting the bed frame to be transversely tipped, and mechanism for tipping the bed frame and positively securing it at any position within the limits of its adjustability, said mechanism including a downwardly projecting arm affixed to the central portion of the bed frame, a screw threaded shaft journaled in bearings on the main frame, a nut engaged with the said shaft and having a sliding engagement with the arm, means for preventing the rotation of the nut with the shaft, and means operable from the exterior of the main frame for rotating the shaft.

2. An adjustable bedstead comprising a main frame, a pivoted bed frame adapted to be transversely tipped relatively to the main frame, and having a hinged head section, the main portion of the pivoted bed frame having a downwardly projecting arm, mechanism supported by the main frame and cooperating with said arm in transversely tipping the bed frame and securing it at any position within the limits of its tipping movement, and mechanism supported by the pivoted bed frame for imparting a swinging adjustment to the head section thereof, and positively securing the latter in any position to which it may be adjusted.

3. An adjustable bedstead comprising a main frame, a bed frame having head and body sections pivotally connected together and having a wire mattress, means for independently adjusting the longitudinal inclination of the head and body sections, and independent spring supports extending transversely of the bed frame at the pivotal point of its sections.

4. An adjustable bedstead comprising a main frame, a bed frame having head and body sections pivotally connected together and having a wire mattress, means for independently adjusting the longitudinal inclination of the head and body sections, and independent spring supports extending transversely of the bed frame at the pivotal point of its sections, said spring supports comprising a plurality of sockets, a stationary bar to which said sockets are connected, springs mounted in said sockets, and plun-

gers supported by said springs and connected to the mattress of the bed frame.

5. An adjustable bedstead comprising a main frame, two pivotally connected bed frame sections having their outer ends pivotally supported by the main frame whereby the bed frame may tilt laterally as a whole, an arm carried by the bed frame and having a nut at its lower end, a screw shaft 20 mounted in the main frame and engaging said nut, and means for independently adjusting the inclination of the bed frame sections, said adjusting means for each section comprising a pendent screw, a rotatably 25 mounted nut fitting said screw and having a pinion, and a crank shaft having a pinion meshing with the pinion of said nut.

0 mounted in the main frame and engaging said nut, and means for independently adjusting the inclination of the bed frame sections.

15. An adjustable bedstead comprising a main frame, two pivotally connected bed frame sections having their outer ends pivotally supported by the main frame whereby the bed frame may tilt laterally as a

whole, an arm carried by the bed frame and having a nut at its lower end, a screw shaft 20 mounted in the main frame and engaging said nut, and means for independently adjusting the inclination of the bed frame sections, said adjusting means for each section comprising a pendent screw, a rotatably 25 mounted nut fitting said screw and having a pinion, and a crank shaft having a pinion meshing with the pinion of said nut.

In testimony whereof I have affixed my signature, in presence of two witnesses.

ELIZABETH J. SAVAGE,
Administratrix of the estate of Thomas C.

Robinson, deceased.
